ABSTRACT OF THE DISCLOSURE

In a low cost yoke for a cathode ray tube deflection system, a core structure encloses the neck of the cathode ray tube; a plurality of helical windings encircle and are peripherally spaced around the core; and each of the windings comprises a foil strip encircling the core in a plurality of turns. The individual turns of each winding are mutually insulated by an anodized film coating the foil strips and serving as layers of insulation material.

BACKGROUND OF THE INVENTION

The invention relates to a yoke for a cathode ray tube deflection system, and more specifically, it relates to the construction of the deflector coils on the yoke.

In cathode ray tubes of the prior art, a yoke with deflection coils comprising wire windings has been utilized to provide the necessary horizontal and vertical deflection of the electron beam to effect a scanning of the cathode ray tube screen. Although the shapes of the yokes have varied, the deflection coils have generally comprised wires which are concentrically wound on the periphery of the core. Even though the deflection achieved by the wire windings is adequate, the wire windings on the yokes are relatively expensive. Furthermore, the wire windings when electrically connected to a high frequency source of horizontal deflection signals in the conventional television set are subject to considerably eddy current losses.

SUMMARY OF THE INVENTION

It is an object of this invention to provide a yoke for a cathode ray tube deflection system at a reduced cost.

It is still a further object of this invention to provide a yoke for a cathode ray tube deflection system wherein the eddy current losses in the coils of the yoke are minimal.

Briefly stated, and in accordance with certain aspects of this invention, there is provided a deflection yoke for a cathode ray tube comprising a core member adapted to enclose the neck of the cathode ray tube and improved deflection coils encircling the core in a plurality of windings. The windings comprise strips of conductive foil, peripherally spaced along the core, to achieve a low cost, low eddy current loss deflection system.

In accordance with certain and more detailed aspects of this invention, there are provided windings comprising strips of aluminum with an anodized film coating the surfaces of the aluminum strips to provide insulation between the individual turns of the windings.

BRIEF DESCRIPTION OF THE DRAWINGS

The specification concludes with claims particularly pointing out and distinctly claiming the subject matter which I regard as my invention. The invention may also be understood from the following description taken in connection with the accompanying drawings in which:

FIGURE 1 is an end view of a deflection yoke;

FIGURE 2 is an axial view of the deflection yoke of FIGURE 1;

FIGURE 3 is an end view of an alternative deflection yoke; and

2

FIGURE 4 is a schematic view of the deflection yoke of FIGURE 1 in a conventional cathode ray tube deflection system.

DESCRIPTION OF THE PREFERRED EMBODIMENT

As shown in FIGURE 1, the deflection yoke comprises an essentially circular core 10 with deflection coils comprising a plurality of peripheral windings 11, designated as 11a through 11j, appropriately spaced around the core to produce a magnetic field distribution characterized by good linearity, good focus, and good rectangularity. The windings 11 are formed by encircling segments of the core 10 with strips of a metallized paper or foil in the form of spiral windings. As is readily appreciated, the individual turns of the windings must be suitably insulated from each other and the core, and this may be achieved through one of at least two methods.

In a first method, the strips of metallized paper or foil; i.e. aluminum or other type of conductive foil, may be coated with an anodized film on one or both surfaces to effect mutually insulated turns of the windings 11. This process of anodizing would of course provide insulation at the core providing the inner surface is anodized.

Alternatively, each strip of aluminum or conductive foil forming the windings 11 may be wound on the core 10 along with a parallel, discrete strip of insulating material; i.e. paper, to achieve insulation between the individual turns of the windings 11. Again, the inner surface would have to abut the insulating material to insulate the core.

Although the core as shown in FIGURE 1 is essentially circular in cross-section and broken along lines 12 and 13, various alternatives are available in core geometry configurations. For example, the core 10 could be essentially square and comprise a plurality of sections.

FIGURE 2 more fully discloses the nature of the windings 11j, 11a, 11b, 11c, 11d, and 11e, including a lead 17 through which the start of the winding 11b is connected to the finish of the winding 11c. The nature of the deflection coils may be best seen by reference to windings 11d and 11e wherein the various turns take on a laminated appearance. In order to satisfy the impedance requirements of the deflection system, the exact thickness of the windings or required number of turns may be varied and should not result in larger overall yoke dimensions than previously known in the art.

FIGURE 3 discloses a hybrid yoke arrangement embodying the invention in the form of windings 11b, 11c, 11g, and 11h in combination with conventional wire windings 16. Although the expense of the hybrid yoke as disclosed in FIGURE 3 is somewhat greater than that disclosed in FIGURE 1, the hybrid yoke still reaps the benefit of somewhat lower costs and low eddy current losses as long as the higher frequency horizontal deflection signals are applied only to the windings 11b, 11c, 11g, and 11h. Application of the vertical deflection signals to the conventional wire windings 16 produce negligible eddy current losses because of the lower frequency of these signals.

FIGURE 4 illustrates the deflection yoke in combination with a television deflection system including a source of horizontal deflection input signals 14 connected in parallel with a series combination comprising the coils 11h and 11g and a series combination comprising the coils 11b and 11c to produce horizontal scanning of an electron beam. To achieve vertical scanning of the electron beam, a source of vertical deflection input signals 15 is connected in series with the coils 11a, 11j, 11i, 11d, 11e, 11f. Although not shown, it is to be understood that the chosen interconnection may be achieved through leads similar to the lead 17.

The configuration disclosed comprises only ten windings. It is of course appreciated that additional windings and configurations may be provided to achieve the desired deflection required in any particular cathode ray tube.

Although specific embodiments of the invention have been shown and described, it is not desired that the invention be limited to the particular form shown and described and it is intended by the appended claims to cover all modifications within the spirit and scope of the invention.

What is claimed as new and desired to be secured by Letters Patent of the United States is:

1. In a deflection yoke for a cathode ray tube system including a core, the improvement comprising:

deflection coils including a plurality of windings encircling and peripherally spaced along the core, said windings comprising strips of conductive foil encircling the core in a plurality of turns.

2. The invention of claim 1 wherein said plurality of windings include insulation means between each of the plurality of turns of said strips of conductive foil.

3. The invention of claim 2 wherein said insulation means comprises an anodized film on each of said strips of conductive foil.

4. The invention as recited in claim 3 wherein said strips of conductive foil comprise aluminum.

5. The invention of claim 1 further including deflection coils comprising wire windings.

5 6. The invention of claim 2 wherein said insulation means comprises a discrete strip of insulating material parallel with each of said strips of conductive foil.
